UNITED STATES PATENT OFFICE.

PAUL O. SCHILLING, OF HORICON, WISCONSIN.

FENCE-POST.

1,235,845

Specification of Letters Patent. Patented Aug. 7, 1917.

Application filed December 4, 1916. Serial No. 134,993.

To all whom it may concern:

Be it known that I, PAUL O. SCHILLING, a citizen of the United States, residing at Horicon, in the county of Dodge and State of Wisconsin, have invented certain new and useful Improvements in Fence-Posts, of which the following is a specification.

This invention relates to an improved fence post of the metal type and the principal object of the invention is to provide an improved means for engaging line wires to tighten the wires and hold the same in tight engagement with the post.

Another object of the invention is to so construct the fastening device that it may be easily moved to a position to tighten the wires or release them thus permitting the wires to be securely but releasably held in place.

Another object of the invention is to so construct this wire fastener that all of the wires may be secured by the single device and all of the wires tightened by a single operation.

Another object of the invention is to so construct this post and wire fastener that the wires will not be damaged and therefore make it unnecessary to splice the wires in case the line of the fence is changed and the posts brought at different points along the wires from that which they originally occupied.

Another object of the invention is to provide a post and wire fastener which will be very simple in construction but at the same time very strong and durable and serviceable.

This invention is illustrated in the accompanying drawings, wherein:

Fig. 1 is a view showing the improved post in elevation with the wires connected therewith.

Fig. 2 is a view showing the improved post in vertical section with the wire fastener in elevation.

Fig. 3 is a transverse sectional view through the post and wire fastener before the fastener is turned to the operative position, and,

Fig. 4 is a view similar to Fig. 3 with the wire fastener turned to an operative position.

The post 10 may be cast or formed of sheet metal and, as will be seen from an inspection of Fig. 2, is hollow and terminates at its lower end in a penetrating point 11 which permits the post to be easily driven into the ground. The fence wires 12 are passed through the slots 13 in the post and when first put in place will extend transversely through the post as shown in Fig. 3. The securing bar or rod 14 for the wires is positioned in the post between the wires 12 and the slotted portion of the post as shown in Fig. 3 and is provided with lugs 15 having notches formed therein to receive the wires when the securing rod or bar is turned from the position shown in Fig. 3 to that shown in Fig. 4. As this securing rod is turned, the lugs or arms 15 by engaging the wires will force these wires to assume the bent position of Fig. 4 and the wires will thus be held in the stretched and tightened condition, it being of course understood that the wires had previously been tightened by some other device. The fact that the bar 14 is rectangular in cross section will prevent the bar from having a tendency to turn and resume the position shown in Fig. 3 and therefore the wires will not be released until so desired, at which time, the securing bar will be turned by a suitable wrench thus releasing the wires. It will thus be seen that by means of this improved post and securing device, the wires can be securely held in engagement with the post and further held tightly stretched without it being necessary to damage the wires.

What is claimed is:

1. A fence post comprising a hollow body provided with transversely extending slots to receive fence wires extending through the post, and a securing bar rectangular in cross section and extending into the hollow body through the slotted portion thereof and provided with lugs having notches formed therein, the lugs engaging the wires passing through the post with the wires seated in the notches when the securing bar is turned in the post from an inoperative to an operative position.

2. A fence post comprising a hollow body provided with transversely extending slots to receive fence wires extending through the

post, and a securing bar extending into the hollow post through the slotted portion thereof and provided with lugs for engaging the wires passing through the post and bending the wires within the post when the securing bar is turned in the post from an inoperative to an operative position.

In testimony whereof I affix my signature in presence of two witnesses.

PAUL O. SCHILLING.
